BABBITT METAL BAR

Albert H. Jung, Flushing, N. Y.

Application April 28, 1937, Serial No. 139,377

3 Claims. (Cl. 22—136)

This invention relates to molds for the casting of Babbitt metal bars, to the method of making such bars and to the bars made by said method by casting in said molds.

5 Heretofore, it has been customary to cast Babbitt or the like metal in bars about eight and one-half inches long, two and one-quarter inches wide and about three-quarters of an inch deep. Such bars, particularly if containing a high percentage of tin, are tough and extremely difficult to break into pieces small enough to fit into the hand ladle which is generally used to melt the Babbitt preparatory to its use. If put into the ladle for melting purposes without being broken 10 up first, the bar projects beyond the bowl of the hand ladle and only the lowermost part of the bar becomes heated and melts, so that it takes a long time and considerable manipulation to melt the entire bar.

20 My invention therefore contemplates the provision of a Babbitt metal or the like metallic bar which is so constructed that it may readily be broken up into comparatively short lengths of such size that they may easily be inserted into the usual hand ladle used in machine shops and elsewhere for melting such metal.

25 My invention further contemplates the provision of a comparatively easily broken white metal bar in which the areas of breakage are determined by transverse recesses extending from one face of the bar toward the other but without extending into the edges of the bar, so that the side edges and one face of the bar remain completely unmutilated and uninterrupted, while a small amount of metal is left to form the end walls of the recesses and the bottom walls thereof, said walls being a small fraction of the thickness of the remainder of the bar.

30 My invention further contemplates the provision of a mold in which the usual process steps of casting and skimming the bar may be efficiently performed, but in which recess-forming members are removably suspended for ready insertion into the molten metal cast in the mold 40 without interfering with the casting, skimming and removing operations in the process of making the bar.

35 My invention further contemplates the provision of a mold attachment carrying the recess-forming members and provided with self-centering means to insure the formation of unmutilated side edges on the bar cast in the mold.

45 My invention further contemplates the provision of a novel step in the bar-casting process 50 consisting of displacing part of the molten metal

by inserting recess-forming members in the molten metal after the metal has been cast in the mold and skimmed, and the removal of such members after the metal has solidified to permit easy removal of the finished bar from the mold.

5 The various objects of the invention will be clear from the description which follows and from the drawing, in which,

Fig. 1 is a perspective view of a pair of molds to which my invention has been applied, one of the molds being shown as filled with molten metal, while the other mold is shown empty and partly broken away to disclose the interior.

Fig. 2 is a bottom plan view of one form of my new bar.

15 Fig. 3 is a vertical section of the same.

Fig. 4 is a similar section of a modified form of the same.

20 In the practical embodiment of my invention insofar as the bar cast by my new mold is concerned, said bar 10 is preferably made of generally rectangular outline provided with a bottom face 11, an upper face 12 substantially parallel to the face 11, end edges 13 and 14 preferably inclined inwardly from the bottom face 25 to the top face and side edges 15 and 16 also tapering preferably from the bottom face 11 inwardly toward the upper face 12.

25 It will be understood that as is usual, said upper face 12 may contain integrally cast indicia 30 such as lettering, numerals, trade-marks or the like to identify the bar, while the bottom face 11 is generally slightly irregular due to the contraction of the metal on solidifying.

35 Extending from the bottom face 11 toward the top face 12 and arranged transversely of the bar are a series of comparatively deep wedge-shaped recesses 17, 18 and 19 having tapered end and side edges, said recesses being generally parallel and in longitudinal spaced relation along the 40 bar to divide the bar into short integrally joined sections 26, 27, 28 and 29. The recesses, however, are preferably not long enough to extend up to the side edges 15 and 16 but terminates sufficiently inwardly from said side edges to provide connecting wall portions as 20, 21 between the sections 26, 27 and beyond the ends of the recesses. Said connecting portions are preferably made as thin as possible or on the order of $\frac{3}{32}$ inch or less in thickness, yet of sufficient thickness 50 to prevent breakage of the bar under normal and even accidental stresses as for example when the bar is dropped and sufficiently thin to be easily fractured by a sharp blow.

55 As shown in Fig. 3, the recesses 17, 18 and 19

may extend about halfway or slightly more than halfway through the thickness of the bar and in substantial alignment with corresponding similar recesses as 22, 23 extending downwardly from the upper face 12 toward the bottom face 11. The recesses 22, 23 may, if desired, extend completely across the width of the bar since said recesses may be finished in such a manner as not to mar the appearance of the top face 12 and may conform to a design made in said top face. Said recesses, however, may if desired, terminate inwardly of the side edges of the bar in the same manner as the recesses 17, 18 and 19. In any event, the recesses 22 and 23 are sufficiently close to the corresponding recesses 17 and 19 to provide comparatively thin connecting walls as 24, 25 between the adjacent bar sections 26, 27 and 28, 29, said walls forming the bottoms of the recesses and being about one-fifth or less of the thickness of the bar.

As shown in Fig. 4, the recesses as 30, 31 may be made deeper to extend sufficiently close to the top face 12 to make it easy to break the thin connecting wall members 32, 33 when desired without the use of the additional recesses 22, 23. The recesses 32 and 33, similarly to the recesses 17, 18 and 19 do not extend entirely across the bar but terminate preferably close to the side edges 15, 16, whereby said side edges remain unmitigated and uninterrupted.

In order that the bar may be cast in a mold, without interference with the casting operation by the recess-forming members, and to freely permit the skimming of dross from the top of the molten metal in the mold, I provide a mold attachment including means for removably suspending the recess-forming members in the mold interior.

Referring to Fig. 1, the mold 35 is of the usual general form having downwardly and inwardly sloping side walls and having a bottom 36 engraved with the required indicia and provided with suitable projecting portions as 37 designed to form the panelled depressions 38 in the top surface 12 of the bar. As has been hereinbefore indicated, means are provided for removably supporting and suspending the spaced recess-forming members 38, 39 and 40 in the mold interior. Said members are of less length than the width of the mold and of less depth than the depth of the mold, and are of generally wedge-shaped form having tapered end and side edges. An elongated rod as 41 carries the recess-forming members 38, 39 and 40. The upper edge portions of said members are inserted into suitable grooves as 42 in the under face of said rod 41, and fastened by any suitable fastening means such as the screws 43. The rod 41 is hinged at one end, as by means of a hinge pin 44, to a suitable bracket 45, provided with a recess 46 for the reception of the hinged end portion of the rod. By means of the flanges 47, the bracket 45 may be secured to the mold by any suitable means such as the screws or bolts 48, the pin 44 passing through the upstanding walls 49, 50 of the bracket and through the rod 41. At the other end of the mold, a suitable rod centering bracket as 51 is secured as by means of the bolts or screws 52. Said centering bracket is provided with a pair of curved opposed inner walls 53, 54 spaced apart at their lower ends a distance substantially equal to the width of the rod 41, to provide a recess for the reception of the rod. At their upper ends, however, the walls 53 and 54 are curved outwardly away from each other to

provide an entrance space for the rod wider than the width of the rod so that when said rod 41 is swung about its hinge, the walls 53 and 54 guide the rod toward the bottom of the recess between said walls and take up any play which might exist in the hinge pin 49, thereby to position the rod in an exact predetermined position relatively to the mold 35. By so positioning the rod 41, the recess-forming members 38, 39 and 40 are always arranged in the exact predetermined position required, with the ends thereof spaced the required amount from the sides of the mold 35.

Preliminary to casting the babbitt or other metallic bar in the mold, the rod 41 is raised about its hinge pin to rest against the inclined surface 55 of the bracket 45, thereby removing the recess-forming members from the mold and exposing the entire upper surface thereof for the free pouring of the molten metal thereinto. The molten metal is next poured into the mold to the proper height and the upper surface of the molten metal is cleaned and skimmed to remove the dross therefrom. After skimming, the rod 41 is swung into the position shown in Fig. 1, wherein the free end thereof enters the centering bracket 51 thus carrying the recess-forming members 38, 39, 40 into the molten metal, and displacing the required wedge-shaped sections of the molten metal. When the metal has solidified in the mold, the rod 41 is raised, thereby removing the recess-forming members from the cast bar 10 and freeing the top of the mold for the removal of the cast bar therefrom.

It will be seen that I have provided a metallic bar provided with suitable recesses forming reduced cross-sectional areas, whereby it may be broken into short lengths readily, the recesses being so arranged as to prevent mutilation of the top and side edges of the bar; that I have provided a simple and efficient mold for the production of such cast bars as well as an efficient and easily carried out process for forming the recesses.

While I have shown and described certain specific embodiments of my invention, I do not wish to be understood as limiting myself thereto, since I intend to claim my invention as broadly as may be permitted by the state of the prior art and the scope of the appended claims.

I claim:

1. An elongated bar of metal having a relatively low fusing point, said bar being transversely grooved on one side to divide the bar into substantially rectangular segments, said bar being indented on its opposite side at an area corresponding to the grooved formation on the first side, whereby the grooved formation and the indented formation will be one below the other, said indented formation extending transversely through only a portion of the bar to form a section at the grooved formation of relatively small area and high resistance to bending whereby the bar will not readily bend during handling or shipment and simultaneously present but a small cross sectional area for shearing or breakage as by a sharp blow.

2. An elongated bar of metal having a relatively low fusing point, said bar being transversely deformed to provide a weakened section and to divide the bar into substantially rectangular segments, said weakened section extending transversely of the bar and being relatively thin throughout most of its length, and a pair of generally vertical extensions formed integral with

the ends of the relatively thin portion, said vertical extensions being of less height than the height of the bar, whereby said section is relatively small in area to facilitate shearing or breakage as by a sharp blow but has a high resistance to bending to prevent premature distortion during handling or shipment.

5 3. An elongated bar of metal having a relatively low fusing point, said bar being transversely 10 grooved to divide the bar into substantially rectangular segments and to form a relatively

weakened section of a length corresponding to the width of the bar, said weakened section having a relatively thin elongated horizontal portion and a generally vertical extension of less height than the height of said bar, whereby said section is relatively small in area to facilitate shearing or breakage as by a sharp blow but has a high resistance to bending to prevent premature distortion during handling or shipment.

5
